UNITED STATES PATENT OFFICE.

BENGT M. W. HANSON, OF HARTFORD, CONNECTICUT, ASSIGNOR TO PRATT & WHITNEY COMPANY, OF HARTFORD, CONNECTICUT, A CORPORATION OF NEW JERSEY.

HEAD-STOCK.

1,182,170.

Specification of Letters Patent.

Patented May 9, 1916.

Application filed January 10, 1916. Serial No. 71,317.

To all whom it may concern:

Be it known that I, BENGT M. W. HANSON, a citizen of the United States, residing at Hartford, in the county of Hartford and 5 State of Connecticut, have invented certain new and useful Improvements in Head-Stocks, of which the following is a specification.

This invention relates to head-stocks.

10 A head-stock involving my invention is susceptible of advantageous use in conjunction with or as part of a metal working machine of any suitable kind, a specific example of which is a lathe.

15 One of the primary purposes of the invention is the provision of means by which the work can be readily mounted in co-operative relation with the head-stock and properly and correctly driven with the spindle.

20 In the drawings accompanying and forming part of the present specification I have shown in detail one form of embodiment of the invention which to enable those skilled in the art to practice the same will be set 25 forth fully in the following description. I do not restrict myself to said disclosure; I may depart therefrom in several respects within the scope of the invention defined by the claims following said description.

30 Referring to said drawings: Figure 1 is a side elevation partly in section of a head-stock involving the invention. Fig. 2 is an elevation of certain of the operative parts of the head-stock removed from the supporting structure, the spindle being broken away. Fig. 3 is a detail view in sectional elevation of a portion of the spindle, the endwise-movable rod, and the levers for advancing the rod.

40 Like characters refer to like parts throughout the several views.

As already noted, a head-stock comprising the invention is susceptible of incorporation with utility in various types of metal 45 working machines. In Fig. 1 the numeral 2 is assumed to represent in part the bed of a lathe carrying the head-stock, the body 3 of which may as is usual in machines of the art, be adjustable longitudinally of the bed

50 2. This body 3 is, however, normally fixed or relatively stationary. At the inner end of the body 3 is a bearing 4, while at the rear or outer end is a practically similar bearing 5, the two bearings presenting a convenient 55 supporting means for the rotary spindle 6.

The forward or inner end of the spindle is shown provided with a fork 7, the branches of which are connected by a bridge-piece 8 having the center 9, the cone-pointed end of which is adapted to fit a depression in the 60 work 10. It will, therefore, be clear that the center 9 rotates with the spindle 6.

The spindle 6 carries between the bearings 4 and 5 the pulleys 11 and 12, loose on and tight with respect to the spindle. When a 65 driving belt (not shown) is on the pulley 12, it will be clear that the spindle 6 and therefore the center 9 will be rotated, whereas if the belt be shifted to the pulley 11, the rotation of the spindle will be arrested. 70 While the pulley 11 is actually carried by the spindle 6, it is not in the present case directly supported thereby, a bushing fitting in the pulley and surrounding the spindle as common in this art. 75

In conjunction with the spindle 6 and center 9 or equivalents, I provide means for driving the work, the driving means being rotative with the spindle. I provide as will hereinafter more particularly appear driving means of novel construction. Between the branches of the forked head 7 are mounted jaw members as 13 and 14. As shown these jaw members are pivotally mounted between their ends, being approximately diametrically opposite each other and being pivoted as at 15 between the sides of the fork or slotted head 7. The pivots 15 are so positioned that each of the jaw members 13 and 14 will have a long and a short 85 arm, the gripping or work engaging portions of the jaw members 13 and 14 being on the short arms thereof and being made in the form of concaved seats. 90

I provide means for setting the jaw members 13 and 14 in such manner that said jaw members will engage the work with equal pressure, a floating equalizing member as 16 answering satisfactorily in this connection. This floating member 16 may as shown 100 consist of an elongated bar positioned between the sides of the slotted head or fork 7, extending oppositely therefrom and engaging near its ends the rounded free ends of the long arms of the two lever-like jaw 105 members 13 and 14. I may if desired interpose between the equalizing member 16 and the jaw members 13 and 14 springs as 18 which act against the short arms of the said jaw members and thus tend to nor- 110

5 mally open or spread apart the work-engaging arms of said jaw members. The equalizing member 16 may be operated in any desirable manner for instance by the rod 19 which acts against said equalizing member practically midway of the length thereof, the latter as shown having a socket 10 in its rear side to receive the front end of the rod 19. Said rod 19 extends lengthwise 15 of and along the longitudinal bore of the hollow spindle 6 and as shown has the opposite fins or wings 21 projecting through diametrically opposite slots 22 formed in said spindle and intersecting the bore thereof, these wings or fins presenting a convenient 20 way of keying the rod and spindle together. The wings also present suitable projections to be engaged by levers or equivalent means (hereinafter described) by which the rod 19 and hence the actuating equalizing member 16 can be advanced to set the two jaw members 13 and 14.

25 Threaded onto the extreme outer end of the hollow or tubular spindle 6 is a nut 23 constituting a suitable carrier for the diametrically opposite levers 24 of approximately angular form and pivoted at their 30 angles in slots in the forward side of said nut, the toes of the levers being coöperative 35 with the wings or projections 21. Slidable on the rear or outer portion of the said spindle is a sleeve 25 which with the cone-shaped portion 26 thereof constitutes a suitable actuator for the levers 24, the free portions of the long arms of the levers constantly lying against the cone surface or portion 26. Supported for sliding movement by the rear bearing 5 is the bar 27 having a finger 28 disposed in the peripheral groove 29 of the slidable cone sleeve 25. This bar presents a suitable means for operating said cone sleeve. To move the bar back and forth 40 to effect the gripping or releasing movements of the jaw members 13 and 14 through the intervening parts, the lever 30 may be provided, this lever 30 being pivoted as at 45 31 to the bracket 32 on the bearing 5 and the inner arm extending through a slot 33 in said bearing and entering a slot 34 in the slidable bar 27 between the ends thereof. It follows that if the forward or manipulating 50 arm of the lever 30 be swung to the right in Figs. 1 and 2, it imparts an opposite movement to the bar 27, so that the latter in turn 55 can through the intermediate parts close the jaw members 13 and 14 upon the work 10. It will be understood that the front end of the rod 19 projects slightly beyond the forward end of the bore or longitudinally extending 60 passage of the spindle 6. This rod 19 except where it is enlarged as at 19' is free of the wall of the bore, the enlargement 19' being back of the front end of the rod, the forward portion therefore, of the rod 65 being susceptible of a certain amount of

70 lateral movement in all directions, by reason of which said forward portion can in effect float with the equalizing member 16. As the enlarged portion 19' has a sliding contact with the wall of said bore, the rod 19 will be 75 accurately guided.

75 It will be assumed that the free ends of the levers 24 are upon a low part of the cone surface 26, that the lever 30, bar 27, rod 19 and equalizing member 16 are in their retractive positions. It follows, therefore, that the two springs 18 acting against the jaw members 13 and 14 will yieldingly hold said jaw members in their expanded or open relation, so that the work 10 can be positioned on the 80 center 9. It will be assumed that the work is thus located and that it is desired to clamp the same. In this event the outer or manipulating arm of the lever 30 is advanced or swung toward the right in Figs. 1 and 2, the 85 bar 27 being moved to the left and correspondingly moving the sleeve 27 so that the free portions of the levers 24 will be caused to ride up the cone surface 26, the toes of the levers acting against the wings 21 advancing 90 the rod 19 or moving the same toward the right in Figs. 1 and 2, thereby imparting a corresponding movement to the equalizing or rocking member 16. As the equalizing member is thus moved forward it acts 95 against the jaw members 14 so as to set the same with identical pressures upon the work 10, the result being that there is no possibility of the work being thrown off center, although it will be properly driven. In Figs. 100 1 and 2 the parts are shown as occupying their advanced or operative positions.

105 In Fig. 1 the casing 35 incloses change gearing for driving a cam shaft (not shown). These features constitute no part 110 of the present case. Above the slidable bar 27 is a belt shifting member 36 provided with a loop 37 to receive the belt movable between the pulleys 11 and 12. This belt shifting member 36 is also equipped with a 115 brake member 38 adapted to engage the fast pulley 12 just about the time the belt is shifted from said fast pulley on the loose pulley 11. This belt shifter 36 can be operated by the hand lever 39 or can be operated mechanically by the element 40. The belt shifting and pulley brake means, however, constitute 120 no part of the present application.

125 It will be clear from the foregoing description taken in connection with the annexed drawings, that I provide a live spindle and means rotative with the spindle for driving the work and automatically adjustable to the form of the work. The automatically adjustable means consists as 130 shown of a pair of jaw members which are made thus automatically adjustable through the intervention of a floating or bodily movable member. It will be assumed that the rod 19 and floating or equalizing mem- 135

ber 16 are in the back positions and that as a consequence the jaw members 13 and 14 are open and that a piece of work as 10 is mounted on the center 9. It will be further supposed that that part of the work which is to be gripped by the jaw members when the same are closed is eccentric, for instance on the upper side thereof. To grip or chuck and therefore effect the driving of the work when the spindle 6 is rotated, the rod 19 is thrust forward in the manner already described, consequently imparting a corresponding movement to the floating or equalizing member 16. As the latter is advanced, it acts against the rounded free ends of the jaw members and tends to set them. If as in the illustration noted the upper part of the work be eccentric, the jaw member 14 will first engage the work, after which the floating member 16 will in the present case tip and then move the lower jaw member 13 into engagement with what is supposed to be the cylindrical portion of the work and without the upper jaw applying a thrust to the work in a direction tending to displace the same laterally or to move it off center. When both jaws engage the work and on the continued forward movement of the rod 19, said rod acting against the floating or equalizing member 16 causes the latter, after the work is engaged by the jaw members, to impart equal thrusts to the jaw members, so that on the final setting operation the two jaws exactly balance each other, in view of which the work cannot be moved off center. That is to say if one jaw member meets or engages the work before the other owing to the eccentricity of said work, further closing movement of the jaw member in question will be arrested by the work, the pressure of the jaw member being insufficient to displace the work. Beyond this point the thrust of the equalizing member 16 is applied solely to the companion jaw member until such point as the latter engages the work at which time as already noted, identical closing effects will be applied to the two jaw members, in view of which circumstance displacement off center of the work is effectually prevented.

What I claim is:

1. The combination of a live spindle, work gripping jaw members supported by the live spindle, a rod in the live spindle, and a floating member between the rod and the

jaw members, and means to advance the rod and thereby the floating member to set the jaw members.

2. The combination of a live spindle, a pair of pivotally supported, approximately diametrically opposite jaw members carried by the spindle, an endwise movable rod supported by the spindle, a floating member between the rod and the jaw members, and means for advancing the rod and thereby the floating member to effect the setting of the jaw members.

3. The combination of a hollow live spindle having a fork at the front end, jaw members pivotally supported by the fork, a floating member in the fork, engaging the free ends of the jaw members, a rod in the spindle engaging the floating member, and means for advancing the rod and therefore the floating member to effect the setting of the jaw members.

4. The combination of a live spindle, jaw members supported by the live spindle for rotation therewith, a floating member engaging the jaw members, an endwise movable rod in the spindle, provided with projections, the spindle being slotted for the passage of the projections, levers to engage the projections, and a cone sleeve slideable on the spindle for operating against the levers to cause the same through said projections to impart an advancing movement to said rod.

5. The combination of a live spindle, work gripping jaw members of angular form pivotally supported approximately at their angles and diametrically opposite each other, one branch of each jaw member being adapted to engage the work, a floating member to engage the other branches of the jaw members, and means for imparting a jaw member setting movement to said floating member.

6. The combination of a live spindle, work gripping jaw members rotative with said spindle, a floating member for setting the jaw members, and means inclosed by the spindle for operating the floating member to effect the setting of the jaw members.

In testimony whereof I affix my signature in presence of two witnesses.

BENGT M. W. HANSON.
